UNITED STATES PATENT OFFICE.

WILLIAM O. BECK, OF RIDGEFIELD, NEW JERSEY, ASSIGNOR TO WESTERN ELECTRIC COMPANY, OF NEW YORK, N. Y., A CORPORATION OF ILLINOIS.

SUBSTATION TELEPHONE SET.

1,071,601.

Specification of Letters Patent. Patented Aug. 26, 1913.

Application filed February 16, 1912. Serial No. 677,965.

To all whom it may concern:

Be it known that I, WILLIAM O. BECK, citizen of the United States, residing at Ridgefield, in the county of Bergen and 5 State of New Jersey, have invented a certain new and useful Improvement in Substation Telephone Sets, of which the following is a full, clear, concise, and exact description.

This invention relates to telephone sub-10 scribers sets and more particularly to improvements in metal subscriber sets.

The object of this invention is to provide a novel and convenient means for attaching a metal shelf to a subscriber set box in such 15 a manner as to use the minimum number of mounting screws and still insure that the attachment will be in perfect alinement with the set to which it is attached.

In a subscriber set embodying this invention the back member of the telephone box 20 is provided with notches adapted to engage lugs upon a shelf supporting member to retain said member in place with the shelf in alinement with said box.

25 In the drawings illustrating this invention Figure 1 is a front elevation of a subscriber box with the shelf attachment. Fig. 2 is a detail sectional view of parts shown in Fig. 1 and Fig. 3 is a fragmentary detail 30 view of the locking means.

As shown in the drawings 5 designates a metal subscriber set box carrying a transmitter 6, a pair of gongs 7, 7 and a switch hook 8 for supporting a receiver 9. Within 35 the box 5 may be mounted a condenser, an induction coil and ringer spools none of which is shown. For supporting the box 5 upon a wall or other suitable support such as the back board 10 there is provided a 40 frame member 11 which is turned over at its edges to form a flange 12. The box 5 is hinged to this frame member and said member may be attached to the wall or other support by means of suitable screws inserted 45 from the front thereof from within the box.

Carried by a supporting member 15 is a diagonally arranged shelf 16 having one end attached to said member 15 and being

further supported by means of diagonally arranged braces 17, 17 the outer ends of 50 which are attached to the lower face of the shelf and the inner ends of which are attached to the supporting member 16. The edge of said supporting member is turned over to form a flange 18. Formed upon the 55 flanged portion of the upper end of the supporting member 16 are two T shaped lugs 20, 20 having their ends 21, 21 bent or turned outwardly. The flange portion at the lower end of the frame member 11 is 60 provided with two laterally separated notches 22, 22 spaced the same distance apart as the lugs 20, 20. The depth of said notches 22, 22 is the same as the thickness of the metal from which the lugs 20, 20 are formed 65 and are engaged by said lugs with the turned over portions thereof resting upon the flange of the frame member 11. With the lugs 20, 20 in the notches 22, 22 and the frame piece 11 clamped tightly against its support the 70 mounting member 16 will automatically aline itself with the box 5 and will be held against lateral movement by means of the projections on the lugs 20, 20. The depth of the notches 22, 22 being the same as the 75 thickness of the metal from which the lugs 20, 20 are formed said lugs will be clamped tightly against the support to which the box is attached. Screws 25, 25 may be inserted near the lower margin of the member 16 to 80 assist in maintaining said member in position.

The principal advantage of the scheme described is that it avoids the use of numerous screws and insures that the shelf will be held 85 rigidly and in perfect alinement with the subscriber set box.

What I claim is—

1. In combination, a telephone set box, a frame member therefor adapted to be secured to a support, a flange upon said frame member provided with laterally separated notches, a shelf supporting member and lugs on said shelf supporting member co-operating with the notches in said flange. 95
2. In combination, a telephone set, a

metal frame member therefor adapted to be secured to a support, a flange thereon provided with two laterally separated notches of a depth equal to the thickness of the metal in which they are formed, a metal shelf supporting member, a flange thereon, lugs formed thereon adapted to engage said notches and projections on said lugs adapt-

ed to engage the flange on said frame member.

In witness whereof, I hereunto subscribe my name this 13th day of Feb. A. D., 1912.

WILLIAM O. BECK.
